UNITED STATES PATENT OFFICE.

JOSEPH J. SMITH, OF CAMBRIDGE, MASSACHUSETTS, ASSIGNOR TO WILLIAM FIRTH, OF CHESTNUT HILL, MASSACHUSETTS.

PNEUMATIC BLOWING-MACHINE.

1,193,475.

Specification of Letters Patent.

Patented Aug. 1, 1916.

Application filed January 19, 1914. Serial No. 813,107.

To all whom it may concern:

Be it known that I, JOSEPH J. SMITH, a citizen of the United States, residing at Cambridge, in the county of Middlesex and State of Massachusetts, have invented a certain new and useful Pneumatic Blowing-Machine, of which the following is a specification, reference being had to the accompanying drawings, forming part thereof.

10 This invention has reference to improvements in pneumatic machines for blowing dust and lint sidewise from the path of movement of the machine and adapted particularly for use in mills in which looms and 15 other machines are fixedly arranged along aisles whereby the moving of one of these machines along one aisle may effect the blowing of dust and lint under the fixed machines into the next adjacent aisles to be 20 gathered up in a suitable manner.

The object of the invention is to provide a simple, durable and efficient machine of this nature preferably having a traction driven fan and mouths for delivering air 25 currents laterally.

Other objects of the invention will appear from the following description.

The invention consists in the novel pneumatic blowing machine hereinafter to be 30 more fully described and pointed out in the claim.

Figure 1, represents a side view of the improved blowing machine. Fig. 2, represents a plan view of the same parts of the 35 gear casing being broken away. Fig. 3, represents a front view of the machine, part of the arm carrying the caster wheel and part of the mouth piece being broken away and the location of the machines from which 40 dust and lint may be blown by this blowing machine being indicated.

Similar characters of reference designate corresponding parts throughout.

In factories generally and particularly in 45 cotton mills looms and other machines adapted to operate on material are usually fixedly arranged along aisles and it is desirable from time to time to remove dust, lint and other foreign matter from beneath 50 said fixed machines. In carrying my invention into practice I have had the object of providing a simple and effective machine adapted to be driven or moved along one of said aisles and adapted to deliver air under

pressure laterally whereby the dust, lint or 55 other matter accumulated under said fixed machine could be driven from beneath the fixed machine into the next adjacent aisles where such matter conveniently could be gathered for removal.

As shown in the drawings, in its preferred 60 form, my improved blowing machine comprises a frame having the side plates 5, 5 having the recessed wheel receiving compartments 6, 6 and the forward extensions 65 7, 7 connected by the cross member 8 from which depends the arm 9 carrying the caster wheel 10; the compartments 6, 6 being connected by the cross member 11. Mounted on said plates 5, 5 are the standards 12, 12 70 which at their upper ends are connected with the cross bar 13 and with the bent members 14, 14 of the uprights 15, 15 the latter of which are mounted on the extensions 7, 7 of the side plates 5, 5. Pivotedly mounted on 75 studs 16, 16 of the standards 12, 12 are the handle side arms 17, 17 having the handle 18 and notches 19, 19 adapted to engage the pins 20, 20 of the members 14, 14 so that when this machine is out of use the handle 80 arms may be swung down to the sides of members 14, 14.

Mounted on the cross member 11 is the fan chamber 21 having the outlet 22 which communicates with the mouth piece 23 carried 85 by the cross member 8 and having the transversely extending outlets or mouths 24, 24 adapted to deliver at the sides of the machine forward of the wheels thereof. At the juncture of the diverging outlets 24, 24 90 is journaled the shaft 25 having, inside said mouth piece, the valve or damper 26 and, at its outer end, the handle or lever 27, whereby said damper 26 may be swung to close either of said outlets 24, 24 or said 95 damper 26 may be positioned vertically to permit air to pass out of both of said outlets. The means for holding said damper 26 in its vertical position may be the frictional engagement of shaft 25 in its bearing or any 100 other well known means which is not shown as it forms no part of the present invention.

At the side of the fan casing 21 is the gear case 28 having the rotatable fan shaft 29 105 furnished with the pinion 30 which is driven by the large gear 31 of the rotatable shaft 32 having the pinion 33 which is driven by

the gear 34 of the shaft 35 journaled in a bearing of the gear case cover and having at its outer end the sprocket 36.

Journalized in bearings of the side plates 5, 5 at the recessed portions forming the wheel compartments 6, 6 is the shaft 37 having thereon the traction wheels 38, 38, which are rotatable within the compartments 6, 6 and on said shaft or axle 37 between said compartments 6, 6 is mounted the sprocket 39 having the chain 40 operating over the sprocket 36 whereby the power exerted by the traction of the wheel 38, 38 is transmitted to said sprocket and thence through its shaft and the gears 34, 33, 31 and 30 to the fan shaft 29 to operate any ordinary fan thereon.

This improved blowing machine is of considerable weight so that the traction wheels 38, 38 and the leverage exerted by their diameters is sufficient under the movement of the machine over a floor or other way to effect the rotation of the fan shaft 29 and any ordinary fan thereon, through the power transmitting gear mechanism, to drive said fan at a speed sufficient to form currents of air through the fan casing 21 and thence through the mouth piece 23 and out of the outlets or nozzles 24, 24 with sufficient pressure to blow dust, lint and other foreign matter along the floor preferably without force sufficient to drive such foreign matter in circulation to any considerable height.

In the particular use of this machine here-in referred to as indicated in Fig. 3 of the drawings *a* and *b*, *b* indicate aisles of a factory along which aisles are arranged rows of machines *c*, *c* which are fixed in place but usually have frames which are open at their lower portions. This improved blowing machine is driven along

one of said aisles and the air issuing from the outlets or nozzles 24, 24 drives the dust, lint and other foreign matter laterally from the sides of aisle *a* and from beneath the machines *c*, *c* into the aisles *b*, *b* where such dust, lint or matter can be gathered for removal without interfering with the operations of the said machines *c*, *c*. When it is desired to deliver the air blast in but one direction through one outlet 24 the damper 26 is swung in a direction to cut off the passage to the other of said outlets or nozzles 24, 24.

Having thus described my invention I claim as new and desire to secure by Letters Patent:

A pneumatic blowing machine of the nature described comprising a frame provided with side plates having wheel receiving recesses, a shaft journaled in bearings of said side plates and having traction wheels positioned in said recesses and a sprocket located between said side plates, a cross member mounted between said side plates, a fan casing mounted on said cross member and having a gear case, an air delivery pipe extending from said fan casing, a mouth piece communicating with said delivery pipe and terminating in diverging nozzles, a rotary fan in said fan casing and having a shaft extending into said gear case, multiplying drive gears for said fan shaft positioned in said gear case one of which gears has a shaft extending outside of said gear case and having a sprocket, and a chain connecting the latter sprocket with the sprocket of the traction wheel shaft.

JOSEPH J. SMITH.
